Patented Feb. 22, 1921.

UNITED STATES PATENT OFFICE.

ARTHUR J. MICHAELS, OF AKRON, OHIO.

HOLDING AND DISPENSING DEVICE.

1,369,693.

Specification of Letters Patent. Patented Feb. 22, 1921.

Application filed May 27, 1920. Serial No. 384,754.

To all whom it may concern:

Be it known that I, ARTHUR J. MICHAELS, a citizen of the United States, residing at Akron, in the county of Summit and State 5 of Ohio, have invented certain new and useful Improvements in Holding and Dispensing Devices, of which the following is a specification.

This invention relates to devices for dispensing paper napkins one at a time, and a small quantity of sugar, enough for one cup of coffee, tea, or other beverage, and has for one of its objects to simplify and improve the construction and increase the efficiency 15 and utility of devices of this character.

With these and other objects in view, the invention consists in certain novel features of construction as hereinafter shown and described and then specifically pointed out in 20 the claims, and in the drawings illustrative of the preferred embodiment of the invention.

Figure 1 is a side elevation with the casting in longitudinal section.

25 Fig. 2 is a front elevation partly in section.

The improved device comprises a casing 10 preferably oblong transversely, and mounted upon suitable stand members 11. 30 Rising from the upper side of the casing 10 is a sugar receptacle preferably formed of a lower part 12 and an upper part 13, the latter having an opening in its upper side provided with a detachable closure 14.

35 Connected to the casing 10, for instance by brackets 15 at its opposite sides, are sugar dispensing devices each comprising a cylindrical body portion 16 having a contracted discharge 17 and a preferably transparent extension 18 with which a conductor tube 19 is connected and leads thence to the sugar receptacle 12-13. By this arrangement the sugar will flow from the receptacle 12 to the cylindrical body 16 through the extension 40 18. Preferably two or more of the sugar dispensing devices will be employed but as they are alike, the description of one will suffice for both.

45 Arranged within the body 16 are coacting swinging leaf valves 20 and 21, and movable through the body 16 between the valves is a spring controlled push pin 22.

At its inner end the pin 22 is connected by links 23 and 24 respectively to the valves, 50 as shown at the right in Fig. 1. The valves

seat at their free ends, when closed, respectively against stop ribs or lugs 25 and 26.

The links 23 and 24 are so proportioned, that when the pin 22 is moved into its outer position, the valve 20 will be open and the valve 21 closed as shown in full lines in Fig. 1, and the sugar will fill the space between the valves, and then when the pin 22 is pushed in, the valves will be reversed in position, or the upper valve closed and the lower valve opened as shown by dotted lines in Fig. 1. By this means when the pin is pushed in, the flow of sugar will be cut off and the quantity between the valves discharged through the contracted opening 17, 55 and then when the pin is released, the spring associated therewith will move the pin outwardly and restore the valves to their former positions, when the sugar will again fill the space between the valves. 75

Thus every time the pin is pushed in a certain quantity of the sugar will be discharged.

The body 16 and the space between the valves will be so proportioned as to contain 80 a certain predetermined quantity, for instance a teaspoonful, and by placing the tea or coffee cup beneath the discharge end of the dispenser, a teaspoonful of sugar will be deposited in the cup every time the pin 85 is actuated.

A flat inverted V-shaped plate 27 is inserted in the sugar receptacle to facilitate the discharge therefrom.

The casing 10 contains paper napkin holding and dispensing mechanism, any required number being employed, but as the holding and dispensing devices are precisely alike the description of one will suffice for all.

Each napkin holding device comprises an inverted U-shaped plate 28 of relatively thin resilient metal having an offset 29 at the end of one of its sides which engages beneath a clip 30 attached to the bottom of the casing 10 and held rigidly in position by a holding rib 31. Attached to the rigidly held side of the member 28 is a spring 32 operating against the free side of the same.

The member 28 is designed to hold paper napkins in superimposed relation represented conventionally at 33, and the rigidly held side of the member 28 is provided with a pointed pin 34 upon which the napkins are impaled, to prevent more than one napkin at a time being removed. 110

Side guard devices 35 are attached to the member 28, to prevent lateral displacement of the napkins.

A feed roller 36 is mounted for rotation near the free end of the member 28, and the napkins are pressed against the roller by the action of the spring 32 and the resiliency of the member 28. Each roller is provided with a turning knob 37, as shown.

10 An opening 38 is formed in the bottom of the casing 10 in vertical alinement with inner face of the roller 36, and attached to the floor or bottom of the casing are coating guide plates 39 including portions depending through the opening and between which the napkins pass, one at a time as the roller 36 is operated.

15 By this arrangement when a napkin is required, the knob 37 is rotated to cause the 20 roller 36 to revolve against the outer napkin which is thus separated from the others and torn loose from the pin 34 and conducted between the guide members 39 and projected a sufficient distance below the floor of the 25 casing to be grasped by the fingers and fully withdrawn. The spring 32 then causes the member 28 to compress the remaining napkins against the roller ready for the next movement of the roller. Thus each time the 30 roller is actuated one napkin and no more will be presented.

The casing 10 is preferably provided with glass panels 40 in its front and rear walls.

15 The improved device is simple in construction, can be inexpensively manufactured of any suitable material and may be in any fanciful design.

20 The preferred embodiment of the invention is disclosed in the drawings and set forth in the specification, but it will be understood that any modifications within the scope of the claims may be made in the

construction without departing from the principle of the invention or sacrificing any of its advantages.

45 What is claimed is:

1. In a device of the class described, a U-shaped holding member rigidly supported at one side and adapted to receive a plurality of napkins in spaced relation, a feed roller, 50 and yieldable means engaging the unattached side of the holding member and maintaining the napkins thereon against the roller.

2. In a device of the class described, a casing, a U-shaped holding member rigidly supported at one side within said casing and adapted to receive a plurality of napkins in spaced relation, a feed roller mounted in said casing, and yieldable means engaging 60 the unattached side of the holding member and maintaining the napkins thereon against the roller.

3. In a device of the class described, a U-shaped holding member of resilient material 65 rigidly supported at one side and adapted to receive a plurality of napkins in spaced relation, and a feed roller against which the napkins carried by the holding member are yieldably maintained.

4. In a device of the class described, a U-shaped holding member rigidly supported at one side and adapted to receive a plurality of napkins in spaced relation, guard devices carried by said holding member to prevent 75 lateral displacement of the napkins, a feed roller, and yieldable means engaging the unattached side of the holding member and maintaining the napkins thereon against the roller.

70 In testimony whereof I affix my signature hereto.

80 ARTHUR J. MICHAELS.
